UNITED STATES PATENT OFFICE

PERLEY R. GLASS, OF WAYLAND, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY

ART OF FOLDING BOOK COVERS

Application filed August 4, 1924. Serial No. 729,930.

This invention relates to the art of folding and more particularly to the folding of the margins of covers of book cases and similar articles over the boards or other backing upon which the covers are mounted, the present invention comprising an improved machine for folding such articles.

In the manufacture of memorandum books, pocket books and similar articles it is customary to attach to a board or backing of paper or cardboard by means of paste a cover of leather, imitation leather, cloth or the like the margins of which extend beyond the edges of the backing; and then to apply paste to these margins and fold them over upon the adjacent margins of the backing.

The corners of covers of the kind referred to above are commonly of two types, rounded and square; the present invention being concerned more particularly with the folding of covers the corners of which are rounded. In one aspect the invention comprises improved means for folding rounded corners. Such a corner should be evenly plaited so that the folded-over margin may be as flat as possible and the folded edge have a smooth contour. According to one feature of the present invention there is provided a forming block having a rounded face adapted to be held against the inner face of the margin at a corner of the cover, means being provided for gathering the margin evenly about the block and for thereafter bending the margin over the adjacent margin of the backing and pressing the fold thus formed. By thus causing the margin first to be gathered about the forming block and then folded over into place, there results a folded corner having a smooth edge and flat, regularly-spaced plait.

The backing which is used varies greatly in stiffness. When such backing is made of cardboard or other stiff material it is possible to fold the margin of the cover directly over the edge of the board, but, when the backing is thin and weak, it is difficult to make a satisfactory fold in this manner. According, therefore, to another feature of the invention, a forming plate is provided over which the margin at the corner of the cover

may be bent to form the fold. Such forming plate may be a thin metal plate of the desired contour which is held pressed against the backing with its edge in register with that of the backing while the margin is first gathered about the forming block and then is bent over the forming plate.

In order to facilitate the presentation of the work in proper position there is provided, according to another feature of the invention, means for locating the work properly by engagement with the straight edges of the work adjacent to a corner thereof; and such means may conveniently consist of two upright plates arranged substantially at right angles to each other and adapted to be lifted at the proper time to permit the folder to move forward.

Referring now to the accompanying drawings there is shown a machine adapted to fold the corners and the connecting straight or moderately curved edges of a piece of work such as part of a pocket book.

Figure 1 is a perspective of a machine for folding the corners and connecting edges of a piece of work.

Fig. 2 is a detail in elevation showing the connection between the one-revolution clutch and the corner guide lifting mechanism,

Fig. 3 is a perspective of a finished piece of work,

Fig. 4 is a vertical longitudinal section through the machine,

Fig. 5 is a perspective showing the work-engaging parts in the position which they occupy at the completion of the folding of a corner,

Figs. 6 to 9, inclusive, show various steps in the operation of folding a rounded corner,

Fig. 10 is a perspective similar to Fig. 5 but showing the work-engaging parts in the position which they occupy after the margin at the corner of the cover has been gathered about the forming block,

Fig. 11 is a perspective of the forming plate and the forming block showing them in the same positions which they occupy in Fig. 10,

Fig. 12 is a perspective showing the mechanism for rendering the clamping arms operative or inoperative,

Fig. 13 is a perspective showing more particularly the mechanism for locking the former and the forming block in their lowered positions,

5 Fig. 14 is a plan of the two-part corner folder and the slide by which it is carried,

Fig. 15 is a view of the corner folder, the slide by which it is carried, the slotted part of the frame in which the rolls carried by 10 the parts of the corner folder run and the folder for those edges of the work which are located between the corners.

The illustrative machine is particularly adapted to the folding of the covers of book cases and parts of pocket books, such work 15 commonly comprising a board or backing 100 of cardboard, paper or other suitable material and a cover 200 of flexible material which is commonly leather, imitation leather or cloth, the cover being larger than the backing and shaped so that its margin projects beyond the edge of the backing. A coating of paste is applied to this projecting margin, after which the margin is folded over 20 and pressed down upon the margin of the backing. Ordinarily a piece of work has 25 four corners, the edges between the corners being straight or only moderately curved. Where rounded corners are desired, the backing 30 is cut with rounded corners and the cover with similarly rounded corners or with cut-off corners and, when the corner of such a cover is folded over the corner of such a backing, the corner of the cover should be evenly 35 plaited as indicated at the corners 300 in Fig. 3. With the present machine the work is commonly first presented to corner-folding mechanism which folds the round corners and then to mechanism for folding the edges 40 between the corners, said last-named mechanism, as will presently appear, being capable of taking care of corners which are square or approximately so.

In Fig. 3 there is shown a piece of work 45 which is part of a fancy pocket book, this piece having been chosen because it has rounded corners, square corners, a straight edge, and edges which are moderately curved. This particular piece of work was presented 50 six times to the machine, once each to the corner-folding mechanism to fold the two round corners and then four times to the edge folding mechanism, first to fold the curved edge 400, second to fold one of the 55 curved edges 500, third to fold the other edge 500, and finally to fold the straight edge 600. It will be noted that the square corners 700 are produced by the edge folding mechanism, the cover having been cut properly to produce the corner shown.

Referring now more particularly to Figs. 5 to 11, a brief description of the mode of operation of the round-corner-folding mechanism will first be given. The portion of 65 work containing the corner to be folded is

placed in the manner shown in Fig. 6 upon a table 19 which is generally triangular in shape, with the projecting margin of the cover resting upon an edge guide 21 having two faces which include between them 75 an angle substantially equal to the angle included between the two substantially straight edges of the backing adjacent to the corner. The shape of the work support 19 as well as that of the edge guide is shown 80 best in Fig. 1, the edge guide having two straight faces arranged at an angle to each other connected by a curved face the curvature of which corresponds substantially to that of the corner desired to be produced on 85 the work, and the cooperating edge of the table being of similar contour.

In order to facilitate the proper location of the work, two corner-guides 22 are provided. These two corner-guides are first 90 lifted to permit the margin of the work at a corner thereof to be pushed beneath them and are then permitted to fall, as shown in Fig. 6. The operator then manipulates the work so that the edges of the backing adjacent the rounded corners thereof are engaged by these corner-guides. Up to this time the forming plate 23 and forming block 25 have been in their raised, inoperative positions, as shown in Figs. 1 and 6. A treadle is now 95 operated to bring these members down into the positions shown in Fig. 7. The forming plate is of generally triangular shape with a rounded end and is nearly large enough to fill the space included between the walls of the edge-guide 21. As the forming plate is 100 brought down it presses the work down firmly upon the table 19, thereby causing the projecting margin of the cover to be bent upwardly against the edge gage 21, as shown in Fig. 7. Power is now applied to the machine 105 through a one-revolution clutch whereupon the following movements take place. The parts of the corner folder 27 move forward 110 and swing together until they occupy the position shown in Fig. 8. In doing this they first gather the corner of the cover about and press it against the forming block 25 and then force the gathered portion beneath and past 115 said block which is yieldingly mounted so as to permit the folder to act in this manner. In Figs. 10 and 11 the work is shown at that 120 stage in which the folder 27 has gathered the margin at the corner of the cover about the forming block. The operative face of the forming block is shaped very much like the inner face of the end of a human finger, being rounded in two directions as shown. The two parts of the folder 27 are shaped as 125 best shown in Figs. 14 and 15. Each part has a forward edge which is arranged at an angle to the forward edge of the other part; and each part is cut away in the locality in 130 which these edges, if extended, would meet, so that when the parts are swung together

there is a substantially U-shaped recess shaped to fit about the adjacent rounded face of the forming block. During the further forward movements of the folder, the forming block drags over the inner face of the margin of the cover. This gathering of the upturned margin about the forming block and the subsequent dragging of the margin frictionally between the folder and the block 10 tends to cause the formation of evenly spaced plaits which are subsequently pressed flat in a manner presently to be described. The next movement of the machine is the withdrawal of the forming plate from beneath the folded-over margin, as shown in Fig. 9. The table 19 then rises to press the fold, and thereafter the parts return to and come to rest in the position shown in Fig. 1. It will be understood that if the backing of the 20 work is stiff enough to permit the cover to be folded over its edge, the forming plate may be dispensed with if desired and the work pressed down upon the table and held in place by the operator.

25 After the two round corners 300 have been folded in the manner described above, the four straight or moderately curved edges 400, 500 and 600 are folded by edge-folding mechanism comprising a stationary edge-guide, having in the present machine three portions of different outlines to correspond one to the straight edge 600, one to the curved edge 400 and one to the two curved edges 500. Referring to Fig. 1, this guide, which is indicated as a whole by the numeral 29, has a straight portion 31, a convexly curved portion 33, and a concavely curved portion 35. Associated with this edge-guide is a folder 37 having an outline to correspond to that of the edge-guide, said folder being connected rigidly with the corner folder slide 39 (Fig. 15) by pins 41 which extend into holes 43 in the folder 37 so that the folder 27 and the folder 37 move forward and back in unison. A table 45 lies in front of the edge guide 29 and is rigidly connected to the triangular table 19 of the corner-folding mechanism so that the two tables move up and down in unison. After the two round corners 300 have been folded on the corner-folding mechanism, the concave edge 400 of the work is presented to the convex portion 33 of the edge guide 29 and the machine put into operation. In this edge-folding mechanism no forming block or forming plate is provided, but otherwise the action of the edge-folding mechanism is much like that of the corner-folding mechanism. The upstanding margin of the corner which projects above the edge guide 29 is pushed over the edge of the backing 100 by the forward movement of the folder 37; and the fold so formed is pressed against the under side of the folder when the table 45 rises. The paste commonly used tends to collect and harden

on the under side of the folders 27 and 37 and to interfere with the proper operation of the machine. In order to overcome this difficulty, a piece of moist absorbent material 47, such as felt, is set into the edge guide 21 in position to moisten the under sides of the corner folders 27; and a similar piece 49 is similarly located with respect to the edge folder 37.

The general construction and mode of operation of the machine having been outlined above, a detailed description of the various mechanisms will now be given.

Referring more particularly to Figs. 1 and 4, the table 45 of the edge-folding mechanism is fast to a casting 51 which is vertically slidable in vertical guideways formed in the frame of the machine; and the table 19 of the corner-folding mechanism has its stem 53 extending into a socket in the same casting and fastened in place by a set screw 55. The casting 51 rests upon two heavy springs, one of which is shown at 57, the lower ends of said springs resting upon nuts, one of which is shown at 59, said nuts being threaded upon the stems of plungers, one of which is shown at 61. The plungers rest upon a plate 63 which is sustained by a square block 64 pivoted to the outer ends of the arms of a forked lever 65 mounted on an eccentric shaft 67 the ends of which are loosely mounted in alined bearings formed in the frame of the machine. The end of the lever 65 remote from the block 64 has a roll 71 which runs on a cam 73 carried by a cam shaft 75. A spring-pressed plunger 77, mounted in a socket in the frame of the machine, tends at all times to hold the roll 71 against the cam 73. With this construction it will be evident that, during a revolution of the shaft 75, the two tables 19 and 45 will be raised in unison to press the fold and then permitted to return to the position shown. The purpose of the eccentric shaft 67 is to permit the initial position of the tables 19 and 45 to be varied so as to provide for different thicknesses of work. To this end (see Fig. 1) a collar 69, pinned to the shaft 67, has an extension provided with a segmental slot 70 and a handle 72 so that, by turning the handle, the shaft 67 may be turned. In order to hold the shaft in any angular position to which it may be turned, a screw bolt 74 extends through the segmental slot, is threaded into a boss on the frame of the machine, and carries a washer 76 and a coiled spring 78. The extension in which the segmental slot 70 is formed, is thus held frictionally against the end of the boss into which the cap screw 74 is threaded.

Turning now to the corner guides 22, these guides are normally in lowered position, as shown in Fig. 1. In the operation of the machine they are first lifted to permit the margin of the cover at the corner to be

slipped beneath them. They are then lowered again so as to permit the corner portion of the work to be properly located by contact of the straight edges of the backing adjacent to the corner with the guides. Power is then applied to the machine to impart one revolution to the shaft 75; and, during this revolution, the corner is folded in the manner which has been described, and the parts of the machine come to rest once more in the position shown in Fig. 1. During this folding operation the corner guides 22 are raised and held raised out of the way of the moving parts of the work-engaging mechanism. To this end (see Fig. 1) the arms 79, at the outer extremities of which the corner guides 22 are carried, are integral with a hub 81 which is fast to a rock-shaft 83 mounted in suitable bearings in the frame of the machine. Also fast to this rock-shaft are two arms 85, 87 carrying respectively at their outer ends rolls 89, 91. The arm 87 is adapted to be lifted by the swinging of a lever 93 (Figs. 1 and 2) pivoted at 95 to the frame of the machine and having at one end a cam 97 arranged to engage the roll 91. This lever is normally held in the position shown by a spring 99 and a stop 101 and has pivoted to its right-hand end the upper end of a rod 103. The lower end of this rod is pivoted to the outer end of an arm 105 which is pivoted at 107 to the frame of the machine and has pivoted to it near its middle the upper end of a treadle rod 109 the lower end of which is connected with the toe end of a heel-and-toe treadle, not shown. It will thus be clear that when the treadle-rod 109 is pulled downward, the lever 93 is rocked in a clockwise direction, the shaft 83 is rocked in the same direction, and the corner guides 22 are raised.

As has been explained, the corner guides 22 are first raised and then allowed to fall before power is applied to the shaft 75 to cause it to make one revolution. The clutch by which power is applied and parts of which are shown in Fig. 2, is thrown into operation by pulling downward on the same rod 103 which causes raising of the corner guides 22. The construction is such, however, that the rod 103 may be pulled down far enough to raise the corner guides without throwing in the clutch. Referring to Fig. 2, the clutch is thrown in when the lever 93 is pulled down far enough to cause the lower end of the arm 110 to contact with and push down the spring-supported dog 111. It will be noted, however, that the arm 110 is spaced somewhat above the dog so that the lever 93 may be pulled down a short distance without affecting the clutch. The clutch itself will not be further described since the details of its construction form no part of the present invention, and any suitable clutch which will impart one revolution to the shaft 75 may be

employed. The constantly rotating member of the present clutch is in the form of a gear 113 which meshes with a gear 115 on the driving shaft 117, said last-named shaft having mounted thereon a fast pulley 119 driven continuously from any suitable source of power by a belt 121.

In order to limit adjustably the normal lowered position of the corner guides 22, a set screw 112 (see Fig. 1) is threaded through one of the arms 79 and contacts at its lower end with the frame of the machine, a lock-nut being provided as shown to prevent it from becoming loose. In order to urge the corner guides continually downward, an arm 114 (see Fig. 2), fast to the rock-shaft 83, has pivoted to its outer end one end of a push-rod 114 the other end of which is slidable through a block 116 carried by the frame of the machine. A coiled spring 118 encircles the rod between the bracket and a collar which is fast to the rod, and urges the rock-shaft 83 at all times to turn in a clockwise direction.

In the operation of the machine, the toe end of the heel-and-toe treadle, not shown, is first depressed slightly so as to raise the corner guides 22 and is then released to permit the corner guides to fall. Next the heel end of the treadle is depressed to bring the forming plate 23 and forming block down into the positions shown in Fig. 6, as will presently be described. Thereafter the toe end of the treadle is pushed down to its full extent and then released. The first part of the downward movement raises the corner guides 22, and the cam 97 holds them raised during the last part of the downward movement which operates through the arm 110 and the dog 111 to throw in the one-revolution clutch, thereby imparting one revolution to the shaft 75. This one revolution, among other things, causes the folder slide 39 to reciprocate; and, in order to hold the corner guides 22 raised during the forward and back movement of the folder slide, there is fast to the upper side of said slide a beveled block 123 upon which the roll 89 rides. The corner guides 22 are thus raised and held raised until the folding and fold-pressing operations are completed, and return to their normal lowered position just as the machine comes to rest.

Turning now to the two folding mechanisms, that for the corners and that for the edges between the corners, the slide 39 (Figs. 4, 14 and 15) is slidable horizontally in suitable ways formed in the machine frame. Fastened to the under side of the slide is a slotted member 125, in the slot in which is received a roll 127 carried at the upper end of an arm 129 which is pivoted to the frame of the machine at 131 and carries, intermediate its ends, a roll 133 which runs in a track 135 formed in a cam 137 fast to the shaft 75. 130

The track is so shaped that, when one revolution is imparted to the shaft 75, the slide 39 is moved forward into the position shown in Figs. 8 and 9, remains in this position while the fold is pressed, and then returns to its initial position shown in Figs. 6 and 7.

Referring now more particularly to Figs. 13, 14 and 15, the two parts of the corner folder 27 are attached to the slide by pivots 139, and each part carries at its rear end a roll 141 which run one in each cam slot 143 formed in a stationary plate 145' which lies above the slide 39. When, therefore, the slide 39 moves forward the parts of the corner folder 27 first move forward, then swing toward each other at their forward ends and then move forward again with the result, as has been explained, that the corner of the cover is first gathered about the forming block, as shown in Figs. 10 and 11, and is then forced beneath said tool.

The edge folder 37 is caused to move forward and back with the slide 39, as has been explained, by reason of the pins 41 in the slide which extend into the holes 43 in the edge folder.

Turning now to the mechanism for operating the forming plate 23 and forming block 25, and referring more particularly to Figs. 1 and 4, the forming plate 23 is fast to the lower end of a stem 145 the split hub at the upper end of which is adjustably fastened to a hollow shaft 147 by a pinch screw 149. The hollow shaft 147 is slidably mounted in a tubular guide 151, and has at its right-hand end, as viewed in Fig. 4, a roll 153 which is received in a segmental cam track 155 in a segmental member 157. A coiled spring 159, located between the left-hand end of the tubular guide 151 and a collar 161 on the hollow shaft 147, prevents chattering of the roll 153 in the cam track 155. The tubular guide, at its rear or right-hand end is forked and the forks terminate respectively in hubs 163, 165 which are fast to alined rock shafts one of which is shown at 167 (Fig. 4). Adjustably fastened to the shaft 167 (see Figs. 1 and 13) is the hub of an arm 171; and to the outer end of the arm is pivoted the upper end of a rod 173, the lower end of which is pivoted to an arm 175 pivoted at 177 to the frame of the machine. Pivoted to this arm intermediate its ends is the upper end of a treadle-rod 179 which is connected with the heel end of the heel-and-toe treadle, not shown, which has been referred to above as having its toe end connected with the treadle-rod 109. It will thus be clear that when the heel end of the treadle is depressed, the forming plate 23 will be brought down from the position shown in Fig. 6 to that shown in Fig. 7. The forming plate, as has been explained above, is held in its lowered position during the formation of the fold as shown in Fig. 8, is then withdrawn as shown in Fig. 9, to permit the fold to be

pressed against the under side of the folder 27 when the table 19 rises, and is finally returned to its initial raised position. The forming plate is normally held in raised position by a spring-pressed plunger 181 carried by the arm 171 and contacting with a stationary abutment 183 (see Fig. 13). A stop screw 180 limits the extent to which the arm may swing upwardly. Pivoted about a stud 182 carried near the outer end of the arm 171 is a latch member comprising a carrier 185, which is normally held in the angular position shown by a spring-pressed plunger 184, and a latch member 189, said latch member being slidable vertically on the inner face of a downward extension 187 of the carrier and having driven into it a pin 191 extending up through a bore in the carrier. A thumb screw 193, threaded into the carrier 185, has a collar 195 extending into a groove in the pin, so that, by turning the thumb screw, the latch member may be adjusted. When the heel end of the treadle referred to above is depressed to pull down the tubular guide 151, the beveled rear face 195 of the latch 189 rides down over a fixed horizontal square rod 197 and locks the tubular guide, and with it the forming plate 23, in its lowermost operative position, as shown in Fig. 13. In order to trip the latch at the proper time after the fold has been formed and pressed, a lever 198 the hub of which is pivoted about the axis of a rod 199 has at its outer end a roll 201 to contact with the beveled face 195 at the proper time and push the latch to the left to disengage it from the square rod 197, this action of the lever 198 taking place when a projection 203 on the cam 137 rides under a roll 207 carried by the lever. A spring-pressed pin 209 holds the roll 207 in contact with the cam.

After the forming plate has been brought down into the position shown in Fig. 8 and before it rises, it is moved into the position shown in Fig. 9 in order to withdraw it from beneath the folded-over margin of the cover. This movement is accomplished by swinging to the left, as viewed in Fig. 4, the segmental member 157. Said member is carried at the upper end of an arm 213 pivoted to the frame of the machine at 215 and having in it a slot 217. Slidable in this slot is a block 219 pivotally and adjustably carried by an arm 221. This arm is rigid with a hub 223 loosely mounted on the rod 199, said hub having also rigid with it a second arm 225 at the outer end of which is a roll 227 which runs in a cam track 229 formed in the farther side, as viewed in Fig. 4, of the cam 137. The two arms 221 and 225 form in effect a bell-crank lever, and, when the shaft 75 makes one revolution, the segmental member 157 is moved to move the creaser 23 from the position shown in Fig. 8 to the position shown in Fig. 9 at the proper time. In order to permit the extent of this movement to be varied as

may be desired provision is made for varying the position of the block 219 in the slot 217. To this end the block is pivotally mounted on the outer end of a pin 231 which has integral with it intermediate its ends a collar 233. The inner end of the pin is threaded to receive a nut 235 against which rests a washer 236. The arm 221 is thus clamped between the washer and the fixed collar 233.

10 The forming block 25 (Figs. 1, 4 and 5) is fast to the downwardly extending end of a bent stem 237, the other end of which is adjustably fastened by a set screw 239 in a socket in one end of a forked member one 15 of the arms of which is shown at 241. These arms are pivoted on alined pins, one of which is shown at 243, which are carried by the tubular guide 151. A spring-pressed plunger 245 tends at all times to swing the forked member 20 in a counter-clockwise direction to an extent limited by a stop-screw 247, both the plunger and the screw being carried by the tubular guide 151. When, therefore, the forming plate 23 is brought down from the position 25 shown in Fig. 6 to that shown in Fig. 7, the forming block 25 is brought down with it and engages the margin of the work yieldingly by reason of the spring-pressed plunger 245. During the subsequent movement of the folder 30 27, the corner of the cover is first gathered about the forming block, as shown in Figs. 10 and 11, and is then pushed beneath the forming block, thereby raising the forming block against the force of the spring-pressed plunger 245. The effect of gathering the corner of the cover about the block and then forcing the gathered corner beneath the block so that said tool drags over the inside of the margin of the corner, is to facilitate the 35 formation of evenly spaced plaits and to draw the cover tightly about the corner of the backing. It will be noted that the margin is frictionally gripped between the folder and the forming block during the folding operation and that because of this grip the cover is 40 drawn tightly about the edge of the backing. Since the forming block is carried by the tubular guide 151, which also carries the forming plate 23, said block rises and comes 45 to rest with the forming plate when the latch 189 is tripped.

When the straight or moderately curved edges which lie between the corners are being folded it is sometimes desirable to provide 50 means for engaging the backing 100 as near its edge as practicable and holding the work down firmly upon the table 45. This means is designed for use more particularly on work the backing of which is flexible. No forming plate is provided with this edge-folding mechanism since it is possible to fold the margins of the edges between the corners without the use of a forming plate. The present machine is provided with such means 55 in the form of two pressers 283, 285 (see

Figs. 1 and 4) which may be held in operative or inoperative position as may be desired. As shown in Figs. 1 and 4 these pressers are in their raised, inoperative position. The presser 283 is carried at the upper end of an arm 287, and the presser 285 at the upper end of an arm 289, the hubs of both arms being fast to a rock-shaft 291 which is rotatably mounted in alined bearings formed in two brackets one of which is shown at 293, said brackets being integral with the casting 51 on which the work tables are mounted. Loose on one end of this rock-shaft is the hub of an arm 295 to the outer end of which is attached the upper end of a treadle-rod 297, the lower end of which is connected to a treadle, not shown. As appears in Fig. 1, this treadle-rod is a two-part rod capable of extension. Referring now to Fig. 12, the pressers 283, 285 are held in raised, inoperative position in the following manner. The hub of the arm 289 has two extensions provided respectively with socketed members 299, 301; and the hub of the arm 295 has integral with it an arm 303 the outer end of which carries a spring-pressed pin 305 in position to engage one or the other of the socketed members according to whether the arm 289 is in its raised or lowered position. As shown in Fig. 12, the arm 289 is in its lowered, operative position being held down by a tension spring 307 the upper end of which is fast to a stationary pin 309 and the lower end to a pin 311 carried by the arm 295. An adjustable stop screw 313, by engagement with the arm 295, limits the extent to which the arm 289 can be swung downwardly. It will, of course, be understood that, when the arm 289 is in lowered position, the arm 287 is also in lowered position since the hubs of both arms 105 are fast to the same rock-shaft 291. In such lowered position the pressers 283, 285 lie so close to the surface of the work table 45 that the work cannot be presented beneath them. When, therefore, the pressers are in their 110 lowered position the treadle, not shown, which is attached to the treadle-rod 297 is depressed to raise the pressers. The work is then pushed over the table 45 beneath the pressers into proper position with respect to 115 the edge-folding mechanism, and the treadle released, whereupon the spring 307 causes the pressers to hold the work firmly in place during the folding operation.

In the description of the mode of operation 120 of the machine as given above, the corners are said to be folded first and then the straight edges; and the corner guides 22 are described as engaging the edges of the backing adjacent to a round corner to facilitate locating 125 the work. The machine, however, may be used to fold the straight edges first up to points spaced from the corners leaving the corners unfolded, after which the work may be presented to the round corner folding 130

mechanism; or the straight edges may be folded by hand prior to the folding of the round corners. In such instances the corner guides 22 do not engage the edges of the backing but engage the cover at localities in which the cover has been folded over the straight edges of the backing.

5 The term "forming block", as used throughout the appended claims, is used to designate 10 a member which has no fold-defining function and at all times during its engagement with the margin of the work engages the inner face of the margin between the fold line and the edge of the margin at a locality 15 opposite to that on the outer face of the margin which is engaged by the operative face of the folder.

20 A machine provided with corner-folding mechanism and edge-folding mechanism by which the corners and edges of a book cover or similar article may be folded is shown and described in prior application Serial No. 656,557, filed August 9, 1923, in my name, and all claims to common subject-matter 25 closed in that application and in the present one are contained in said prior application.

Having described my invention, what I claim as new and desire to secure by Letters Patent of the United States of America is:—

30 1. A machine for folding the margin at the corner of the cover of a book case over the rounded corner of a board thereof having, in combination, a support for the corner portion of the work, a folder movable in a fixed path, a forming block the operative face of which extends above the work a substantial distance, said block having a substantially smooth rounded surface, means for holding the block stationary for a period in the path 35 of movement of the folder and for thereafter permitting it to move away from the folder, means acting to gather the margin about and press it against the block and then to fold the margin over the board, and yielding 40 means for urging the block against the inner face of the margin during the folding operation.

2. A machine of the class described having, in combination, a support for the work, a forming block adapted to contact with the inner face of the margin at a corner of the work, a folder having a recess shaped to fit about the block, means for holding the block stationary for a period in the path of movement of the folder and for thereafter permitting the block to move away from the folder, and means for moving the folder first to cause the margin at the corner of the work to be gathered about and pressed against the forming block and then to cause the margin to be drawn frictionally between the block and the folder and bent over the body portion of the work.

3. A machine of the class described having, 45 in combination, a support for the work, a

forming block adapted to contact with the inner face of the margin at a corner of the work, a folder having a recess shaped to fit about the forming block, means acting prior to the folding operation for holding the block stationary in the path of movement of the folder and for thereafter permitting it to move away from the folder, means for moving the folder first to cause the margin at the corner of the work to be gathered about and pressed against the forming block and then to cause the margin to be drawn between the block and the folder, and means for pressing the fold.

4. A machine for folding the margin at the corner of the cover of a book case over the rounded corner of a book thereof having, in combination, a support for the work, a folder, means for reciprocating the folder and for holding it from lateral oscillation, said folder having a recess in its operative edge the curve at the base of which is more abrupt than that at the round corner of the board, a forming block shaped to fit into the recess, and means for holding the block stationary in the path of movement of the folder and for thereafter permitting it to move away from the folder.

5. A machine for folding the margin at the corners of the cover of a book case over the rounded corners of the board thereof having mechanism constructed and arranged to permit the corner portions of the case to be presented to it in succession, said mechanism comprising a support for a corner portion of the case, a forming block adapted to contact with the inner face of the margin, a folder having converging operative faces and a recess in the locality in which the faces would otherwise meet, said recess being shaped to fit about the front and sides of the block, means for holding the block stationary in the path of movement of the folder and for thereafter permitting it to move away from the folder, and means for moving the folder first to cause the margin at the corner of the cover to be gathered about and pressed against the block and then to cause the margin, while so pressed, to be drawn frictionally between the block and the folder and bent over the board.

6. A machine for folding the margin at the corner of a book case over the rounded corner of a board thereof having, in combination, a support for the work, a forming block adapted to contact with the inner face of the margin, a folder having two converging operative faces, there being a U-shaped recess extending into the folder in the locality in which the converging faces would otherwise meet, the curve at the base of the recess being more abrupt than that at the round corner of the board, and means for moving the folder first to cause the margin to be gathered about and pressed against the forming block and then to cause the margin to be drawn between the block and the folder.

7. A machine of the class described having, in combination, a support for the work, a forming block adapted to contact with the inner face of the margin at a corner of the work, a folder having a substantially U-shaped recess shaped to fit about the adjacent portion of the forming block, and means for moving the folder first to cause the margin at the corner of the work to be gathered about the forming block and then to cause said margin to be drawn beneath said block and laid over into a position parallel to the body portion of the work. 70
- 10 8. A machine of the class described having, in combination, a support for the work, a forming block adapted to contact with the inner face of the margin at a corner of the work, a folder having a substantially U-shaped recess shaped to fit about the adjacent portion of the forming block, means for moving the folder first to cause the margin at the corner of the work to be gathered about the forming block and then to cause said margin to be drawn beneath said block and laid over into a position parallel to the body portion of the work. 75
- 15 9. A machine of the class described having, in combination, a support for the work, a forming block adapted to contact with the inner face of the margin at a corner of the work and a folder adapted to co-operate with the forming block, said folder comprising a plurality of sections, and means for causing them to swing together and to move toward the forming block. 80
- 20 10. A machine of the class described having, in combination, a support for the work, a forming block adapted to contact with the inner face of the margin at the corner of the work and a folder adapted to co-operate with the forming block, said folder comprising a plurality of sections, and means for causing them to swing together and to move toward the forming block, the folders being cut away in such manner that when swung together their forward edge has a recess shaped to fit about the forming block. 85
- 25 11. A machine of the class described having, in combination, a support for the work, a yieldingly mounted forming block adapted to contact with the inner face of the margin at the corner of the work and a folder adapted to co-operate with the forming block, said folder comprising a plurality of sections, and means for causing them to swing together and to move toward the forming block, the folders being cut away in such manner that when swung together their forward edge has a recess shaped to fit about the forming block. 90
- 30 12. A machine of the class described having, in combination, a support for the work, a forming block adapted to contact with the inner face of the margin at a corner of the work, a two-part folder, means for causing the folder to move forward and its parts to swing toward each other first to cause the margin at the corner of the work to be gathered about the forming block and then to cause the margin to be drawn between the block and the folder and laid over into a position parallel to the body portion of the work. 95
- 35 13. A machine of the class described having, in combination, a support for the work, a yieldingly mounted forming block adapted to contact with the inner face of the margin at a corner of the work, a two-part folder, means for causing the folder to move forward and its parts to swing toward each other first to cause the margin at the corner of the work to be gathered about the forming block and then to cause the margin to be drawn between the block and the folder and laid over into a position parallel to the body portion of the work. 100
- 40 14. A machine of the class described having, in combination, a support for the work, a forming plate for defining the line of fold, a forming block, means for causing the forming plate to clamp the body portion of the work against the support and the forming block to be positioned adjacent to the margin at the corner of the work, and means for gathering the margin about the forming block and for laying the margin over into a position parallel to the body portion of the work. 105
- 45 15. A machine of the class described having, in combination, a support for the work, a forming plate for defining the line of fold, a forming block, means for causing the forming plate to clamp the body portion of the work against the support and the forming block to be positioned adjacent to the margin at the corner of the work, a folder, and means for moving the folder first to cause the margin to be gathered about the forming block and then to cause the margin to be drawn between the block and folder and laid over into a position parallel to the body portion of the work. 110
- 50 16. A machine of the class described having, in combination, a support for the work, a forming plate for defining the line of fold, a forming block, means for causing the forming plate to clamp the body portion of the work against the support and the forming block to be positioned adjacent to the margin at the corner of the work, and means for gathering the margin about the forming block and for drawing it beneath said block and laying it over into a position parallel to the body portion of the work. 115
- 55 17. A machine of the class described having, in combination, a support for the work, a forming plate for defining the line of fold, a yieldingly mounted forming block, means for causing the forming plate to clamp the body portion of the work against the support 120
- 60 65 18. A machine of the class described having, in combination, a support for the work, a forming plate for defining the line of fold, a yieldingly mounted forming block, means for causing the forming plate to clamp the body portion of the work against the support 125
19. A machine of the class described having, in combination, a support for the work, a forming plate for defining the line of fold, a yieldingly mounted forming block, means for causing the forming plate to clamp the body portion of the work against the support 130

and the forming block to be positioned adjacent to the margin at the corner of the work, and means for gathering the margin about the forming block and for drawing it beneath said block and laying it over into a position parallel to the body portion of the work.

18. A machine of the class described having, in combination, a support for the work, 10 a forming plate for defining the line of fold, a forming block, means for causing the forming plate to clamp the body portion of the work against the support and the forming block to be positioned adjacent to the margin 15 at the corner of the work, means for gathering the margin about the block and for thereafter bending the margin over the edge of the forming plate, means for withdrawing the forming plate from beneath the folded-over 20 margin, and means for causing relative movement of approach between the folder and the support to press the fold.

19. A machine of the class described having, in combination, a support for the work, 25 a movable carrier located above the support, a forming plate slidably mounted in the carrier, a forming block movably mounted on the carrier, means for moving the carrier downward to bring the forming plate and the 30 forming block into operative position, means for first gathering the margin at the corner of the work about the forming block and for thereafter bending said margin over the forming plate, means for moving the forming 35 plate from beneath the bent-over margin, and means for causing relative movement of approach between the folder and the support to press the fold.

20. A machine of the class described having, in combination, a support for the work, 40 a forming plate, a forming block, means for causing the forming plate to clamp the body portion of the work against the support and the forming block to contact with the margin 45 at the corner of the work, a two-part folder and means for causing the folder to move forward and its parts to move together first to cause the margin at the corner of the work to be gathered about the forming block and then to cause the margin to be drawn between the block and the folder and bent over upon the former.

21. A machine of the class described having, in combination, a support for the work, 55 a forming plate, a yieldingly mounted forming block, means for causing the forming plate to clamp the body portion of the work against the support and the forming block to contact with the margin at the corner of the 60 work, a two-part folder and means for causing the folder to move forward and its parts to move together first to cause the margin at the corner of the work to be gathered about the forming block and then to cause the margin to be drawn between the block and the

folder and bent over upon the forming plate. 22. A machine of the class described having, in combination, a support for the work, a forming plate, a forming block, means for causing the forming plate to clamp the body portion of the work against the support and the forming block to be positioned adjacent to the margin at the corner of the work, a folder adapted to co-operate with the forming block and the forming plate, said folder comprising a plurality of sections, and means for causing them to swing together and to move toward the block and the plate.

23. A machine of the class described having, in combination, a support for the work, 75 a forming plate, a yieldingly mounted forming block, means for causing the former to clamp the body portion of the work against the support and the forming block to be positioned adjacent to the margin at the corner of the work, a folder adapted to co-operate with the forming block and the forming plate, said folder comprising a plurality of sections, and means for causing them to swing together and to move toward the block and the plate.

24. A machine of the class described having, in combination, a support for a piece of work comprising a backing and a cover which projects beyond the edge of the backing, mechanism for folding the margin at the corner of the cover over the margin at the corner of the backing, and means for engaging the edge of the backing adjacent to the corner thereof to facilitate locating the work properly preparatory to the operation of the folding mechanism, said means being normally positioned close to the work support and adapted to be raised to permit the margin of the cover to be thrust beneath it.

25. A machine of the class described having, in combination, a support for a piece of work comprising a backing and a cover which projects beyond the edge of the backing, mechanism for folding the margin at the corner of the cover over the margin at the corner of the backing, a pair of guides disposed at an angle to each other for engaging the edges of the backing adjacent to the corner thereof to facilitate locating the work properly preparatory to the operation of the folding mechanism, and operator-controlled means for moving said guides into operative or inoperative position as may be desired.

26. A machine of the class described having, in combination, a support for a piece of work comprising a backing and a cover which projects beyond the edge of the backing, mechanism for folding the margin at the corner of the cover over the margin at the corner of the backing, means for engaging the edge of the backing adjacent to the corner thereof to facilitate locating the work properly preparatory to the operation of the folding mechanism, and means for moving said means

to and holding it in inoperative position during said folding operation.

27. A machine of the class described having, in combination, corner-folding mechanism and edge-folding mechanism, said last-named mechanism comprising two pressers separate from the folding mechanism adapted to be moved from operative to inoperative positions in paths located one on each side of the corner-folding mechanism.

28. A machine of the class described having mechanism to which the corners of a piece of work may be presented one at a time, said mechanism comprising a support for the corner portion of the work, a forming block adapted to contact with the inner face of the margin at the corner of the work, a folder having a recess shaped to fit about the cooperating side portions of the forming block, said block being located in the path of movement of the folder, means for moving the folder in such manner that the margin is first gathered about and pressed against the forming block and then bent over the body portion of the work to form a fold, and means for causing the fold to be pressed between the support and the folder.

29. A machine of the class described having mechanism to which the corners of a piece of work may be presented one at a time, said mechanism comprising a support having a rounded corner, an edge guide having a contour to correspond to that of the operative portion of the support, a forming plate adapted to press the body portion of the work against the support and thereby to cause the margin at the corner of the work to be bent upwardly against the face of the edge guide, a forming block adapted to be held yieldingly against the inner surface of the upturned margin, a folder for gathering the upturned margin about the forming block and for thereafter causing said margin to be drawn between the tool and folder during the formation of the fold, means for withdrawing the former, and means for pressing the fold.

30. A machine of the class described having mechanism to which the corners of a piece of work may be presented one at a time, said mechanism comprising a support for a corner portion of the work, a forming plate constructed and arranged to press the body portion of the work against the support, means for imparting a bend to a corner portion of the margin of the work, a forming block adapted to engage said bent margin, a folder for bending said margin about the edge of the forming plate to form a fold, and means for producing relative movement of approach between the support and the folder to press the fold.

31. A machine of the class described having, in combination, a support for the work, a forming plate, a forming block, means for causing the work to be engaged by the form-

ing plate and the margin of the work to be bent at an angle to the body portion of the work and for causing the forming block to be positioned adjacent to the bent margin, and means for gathering the margin about the forming block and for laying the margin over into a position parallel to the body portion of the work.

32. A machine of the class described having, in combination, a support for the work, a folder, a forming plate, a forming block, means for causing the work to be engaged by the forming plate and the margin of the work to be bent into the path of movement of the folder, and for causing the forming block to be positioned adjacent to the bent margin, and means for moving the folder first to cause the margin to be gathered about the forming block and then to cause the margin to be drawn between the block and the folder and laid over into a position parallel to the body portion of the work.

33. A machine of the class described having, in combination, a support for the work, a forming plate, a forming block, means for causing the body portion of the work to be clamped between the forming plate and the work support and the margin of the work to be bent at an angle to the body portion thereof, and for causing the forming block to be positioned adjacent to the bent margin, and means for gathering the margin about the forming block and for laying it over into a position parallel to the body portion of the work.

34. A machine of the class described having, in combination, a support for the work, a forming plate, a yieldingly mounted forming block, means for causing the body portion of the work to be clamped between the forming plate and the work support and the margin of the work to be bent at an angle to the body portion thereof, and for causing the forming block to be positioned adjacent to the bent margin, and means for gathering the margin about the forming block and for laying it over into a position parallel to the body portion of the work.

35. A machine of the class described having, in combination, a support for the work, means for imparting a bend to a corner portion of the margin of the work, a forming block having a substantially unbroken rounded surface, means acting first to gather the margin about said rounded surface and then to bend the margin over the body portion of the work, and means for yieldingly holding the block against the inner face of the margin during the bending of the margin.

36. A machine of the class described having, in combination, a support for the work, means for imparting a bend to a corner portion of the margin of the work, a forming block adapted to contact with the inner face of said bent margin, a folder having a recess

shaped to fit about the adjacent portion of the forming block, and means for moving the folder first to cause the margin at the corner of the work to be gathered about the forming block and then to cause the margin to be drawn frictionally between the block and folder and bent over the body portion of the work.

37. A machine of the class described having, in combination, a support for the work, means for imparting a bend to a corner portion of the work, a forming block adapted to contact with the inner face of said bent margin, a folder having a recess shaped to fit about the adjacent portion of the forming block, means for moving the folder first to cause the margin at the corner of the work to be gathered about the forming block and then to cause the margin to be drawn frictionally between the block and folder and bent over the body portion of the work to form a fold, and means for pressing the fold.

38. A machine of the class described having, in combination, a support for the work, means for imparting a bend to a corner portion of the work, a yieldingly mounted forming block adapted to contact with the inner face of said bent margin, a folder having a recess shaped to fit about the adjacent portion of the forming block, and means for moving the folder first to cause the margin at the corner of the work to be gathered about the forming block and then to cause the margin to be drawn frictionally between the block and folder and bent over the body portion of the work.

39. A machine of the class described having, in combination, a support for the work, means for imparting a bend to a corner portion of the work, a forming block adapted to contact with the inner face of said bent margin, a folder having a recess shaped to fit about the adjacent portion of the forming block, and means for moving the folder first to cause the margin at the corner of the work to be gathered about the forming block and then to cause said margin to be drawn beneath said block and laid over into a position parallel to the body portion of the work.

40. A machine of the class described having, in combination, a support for the work, means for imparting a bend to a corner portion of the work, a forming block adapted to contact with the inner face of said bent margin, a folder having a recess shaped to fit about the adjacent portion of the forming block, means for moving the folder first to cause the margin at the corner of the work to be gathered about the forming block and then to cause said margin to be drawn beneath said block and laid over into a position parallel to the body portion of the work to form a fold, and means for pressing the fold.

41. A machine of the class described hav-

ing, in combination, a support for the work, means for imparting a bend to a corner portion of the work, a yieldingly mounted forming block adapted to contact with the inner face of said bent margin, a folder having a recess shaped to fit about the adjacent portion of the forming block, and means for moving the folder first to cause the margin at the corner of the work to be gathered about the forming block and then to cause said margin to be drawn beneath said block and laid over into a position parallel to the body portion of the work.

42. A machine of the class described having, in combination, a support for the work, means for imparting a bend to a corner portion of the work, a forming block adapted to contact with the inner face of said bent margin at the corner of the work and a folder adapted to co-operate with the forming block, said folder comprising a plurality of sections, and means for causing them to swing together and to move toward the block.

43. A machine of the class described having, in combination, a support for the work, means for imparting a bend to a corner portion of the work, a forming block adapted to contact with the inner face of said bent margin at the corner of the work and a folder adapted to co-operate with the forming block, said folder comprising a plurality of sections, and means for causing them to swing together and to move toward the block, the folders being cut away in such manner that when swung together their forward edge has a recess shaped to fit about the block.

44. A machine of the class described having, in combination, a support for the work, means for imparting a bend to a corner portion of the work, a yieldingly mounted forming block adapted to contact with the inner face of said bent margin at the corner of the work and a folder adapted to co-operate with the forming block, said folder comprising a plurality of sections, and means for causing them to swing together and to move toward the block, the folders being cut away in such manner that when swung together their forward edge has a recess shaped to fit about the block.

45. A machine of the class described having, in combination, a support for the work, means for imparting a bend to a corner portion of the work, a forming block adapted to contact with the inner face of said bent margin at a corner of the work, a two-part folder, and means for causing the folder to move forward and its parts to swing toward each other first to cause the margin at the corner of the work to be gathered about the forming block and then to cause the margin to be drawn between the block and the folder and laid over into a position parallel to the body portion of the work.

46. A machine of the class described having, in combination, a support for the work, means for imparting a bend to a corner portion of the work, a yieldingly mounted forming block adapted to contact with the inner face of said bent margin at a corner of the work, a two-part folder, and means for causing the folder to move forward and its parts to swing toward each other first to cause the margin at the corner of the work to be gathered about the forming block and then to cause the margin to be drawn between the block and the folder and laid over into a position parallel to the body portion of the work.

47. A machine of the class described having, in combination, a support for a piece of work comprising a backing having rounded corners and a cover which projects beyond the edge of the backing, a folder, a forming block arranged to contact with the inner face of the margin of the cover during the folding operation, and a pair of spaced guides located one on each side of the forming block and arranged to engage localities on adjacent edges of the backing to facilitate locating the work properly preparatory to the operation of the folder.

48. A machine of the class described having, in combination, a support for the work at a corner thereof, a block having a rounded operative face, a folder having in its edge a recess shaped to fit about said face, the block being located in the path of movement of the folder, and means for operating the folder to cause the margin of the work to be gathered about the block and then to cause the margin to be drawn frictionally from between the edge of the folder and the operative face of the block and, while being so drawn, to be bent over upon the body portion of the work.

49. A machine of the class described having, in combination, a support for the work, a block having a rounded face adapted to contact with the inner face of the margin at a corner of the work, a folder having a recess shaped to fit about the adjacent operative face of the block, a forming plate for determining the line of fold, and means for moving the folder over the body portion of the work whereby the folder first gathers the margin about the rounded face of the block and then moves the block while the margin is being folded about the edge of the former.

50. A machine for folding the margin at the corner of the cover of a book case over the round corner of a board thereof having, in combination, a support for the work, mechanism for folding the margin of the work, spaced guides for engaging the work in localities located one on one side and one on the other side of the corner, and operator-controlled means for moving the guides toward and from operative position.

51. A machine for folding the margin at

the corner of the cover of a book case over the round corner of a board thereof having, in combination, a support for the work, mechanism for folding the margin of the work, spaced guides for engaging the work in localities located one on one side and one on the other side of the corner, and operator-controlled means for raising and lowering the guides.

In testimony whereof I have signed my name to this specification.
